(57) **CLAIM**

The ornamental design for a wire guide, as shown and described.

DESCRIPTION

FIG. 1 is an isometric view of the wire guide;

FIG. 2 is a right side view of the wire guide;

FIG. 3 is a left side view of the wire guide;

FIG. 4 is a front view of the wire guide;

FIG. 5 is a back view of the wire guide;

FIG. 6 is a top view of the wire guide; and,

FIG. 7 is a bottom view of the wire guide.

The broken lines in the drawings depict environmental subject matter only and form no part of the claimed design.
